UNITED STATES PATENT OFFICE.

MORRIS ROSENWASSER, OF NEW YORK, N. Y.

LEGGING-SPRING.

SPECIFICATION forming part of Letters Patent No. 749,951, dated January 19, 1904.

Application filed April 17, 1903. Serial No. 153,006. (No model.)

To all whom it may concern:

Be it known that I, MORRIS ROSENWASSER, residing at New York, in the county of New York and State of New York, have invented 5 certain new and useful Improvements in Legging-Springs, of which the following is a full, clear, and exact description, such as will enable others skilled in the art to which it app pertains to make and use the same.

10 This invention relates to legging-springs; and its object is to provide an improved legging-spring or means for detachably connecting the flaps of a legging, gaiter, or similar article.

15 The invention accordingly consists in the features of construction, combinations of elements, and arrangement of parts, as will be hereinafter fully described, and the novel features thereof pointed out in the claims.

20 In the accompanying drawings, Figure 1 is a side elevation of a legging with the spring members attached thereto in accordance with my invention, one of the flaps being thrown back to show the spring member carried there beneath. Fig. 2 is a perspective showing the 25 springs as they appear when detached and clasped together. Fig. 3 is a detail perspective showing the separate spring members as they appear when unclasped. Fig. 4 illustrates a modification in the form of one of the 30 spring members.

Similar reference characters refer to similar parts throughout the several views.

The upper and lower flaps of the legging A 35 may be identified as B and C. Attached to the flap C by suitable rivets or otherwise is a spring member D, which has a normal curve or tension such that the spring bends or bows outwardly in the center away from the leg of the wearer. Similarly attached to the flap B 40 is a spring member E, consisting of a plain flat strip, which is normally under tension, so that it is curved or bent in the direction opposite to the spring member D or toward the leg of the wearer just prior to the clasping of the two members together.

Each end of the spring member D is provided with an aperture F, which is formed in a part H, which is bent upwardly from the 45 main body of the spring member at an angle

thereto, the material of the spring member being then further bent down, as at K, as shown in Fig. 2. The legging is secured in position by inserting the ends of the spring member E into the apertures F in the ends of its mating spring member, the reverse tension of the two members then counteracting each other and tending to bring the parts into the desired straight position.

55 In Fig. 4 I have illustrated a modification in which the aperture F is formed in the part H, bent up from the main body of the spring member. In this case, however, instead of continuing at an angle to the part H, as in Figs. 1, 2, and 3, a loop or fold is formed having two legs H and L and interposed between the body D of the spring and the continuation M at the end.

60 The general advantages of this invention will be apparent to those skilled in the art. It should be especially noted that I provide a fastener or clasp which may be used, broadly, with a great number of articles and which consists of only two parts, thus making it cheap from the manufacturer's standpoint, 65 simple, not likely to get out of order, and easy to handle during the process of attaching it to the article with which it is to be used or afterward. The opposite curving or bowing of the two members of the clasp or spring provides a spring such that the tendency of one member to buckle or warp out of shape is counteracted by that of the other, and a more easily attached and durable device is obtained.

70 Both from the standpoint of the convenience of the wearer and from the standpoint of the manufacturer desiring to run the legging through a machine or otherwise manipulate it the forming of the main spring member D in one piece is a distinct advantage.

75 Having described my invention, what I claim as new, and desire to secure by Letters Patent, is—

1. A means for connecting the flaps of a legging or similar article, comprising a member 80 adapted to be attached to one flap, said member being bent outwardly at its ends and having apertures in said bent portions, and means in connection with the other flap for engaging said apertures and securing the flaps together. 85

95

100

2. A means for fastening the flaps of leggings or similar articles, comprising a member adapted to be attached to one flap, the material of said member being bent upwardly near its ends and provided with apertures in said bent portions, and a second member adapted to be attached to the other flap provided with parts adapted to enter and be held in said apertures.
- 10 3. In combination, a legging, an integral spring member attached to one flap of the leg-

ging having apertures therein and a second spring member attached to the other flap of the legging and having its ends shaped to engage and be held in the apertures of said first member.

In testimony whereof I affix my signature in the presence of two witnesses.

MORRIS ROSENWASSER.
